UNITED STATES PATENT OFFICE.

LAURENCE A. HAWKINS, OF SCHENECTADY, NEW YORK, ASSIGNOR, BY MESNE ASSIGNMENTS, TO UNION SWITCH AND SIGNAL COMPANY, A CORPORATION OF PENNSYLVANIA.

AUTOMATIC TRAIN-STOP.

1,027,047.

Specification of Letters Patent.

Patented May 21, 1912.

Application filed July 26, 1910. Serial No. 573,908.

To all whom it may concern:

Be it known that I, LAURENCE A. HAWKINS, a citizen of the United States, residing at Schenectady, county of Schenectady, State of New York, have invented certain new and useful Improvements in Automatic Train-Stops, of which the following is a specification.

My invention relates to automatic train stops for use in connection with block signal systems, and particularly to that type of system in which the magnetic continuity of the rails is interrupted at certain points as, for instance, by the insertion of a length of rail of non-magnetic material, such as manganese steel, and in which means is provided for magnetically bridging the spaces which produce this continuity.

My invention consists in providing a magnetic core carried on a vehicle with its poles adjacent to the track rails, a coil on the core, means for supplying alternating current to the coil, and a device on the vehicle responsive to a decrease in the reactance of the coil. When the alternating current magnet on the locomotive or other vehicle is passing over the magnetic running rails, its magnetic circuit is nearly closed, so that the reactance of the winding of the magnet is high. In passing over the non-magnetic rail lengths if these lengths are not magnetically bridged, the reluctance of the magnetic circuit of the alternating current coil is very greatly increased and its reactance is, therefore, greatly diminished. This change in the reactance or in the terminal voltage of the coil may be utilized to actuate a device on the locomotive for giving a warning indication or for applying the brakes. The advantages of using such an alternating current magnet are, first, that very quick action is obtained, since the change in reactance of the alternating current magnet is instantaneous, and, second, that, since the signaling or brake controlling device and all moving parts may be placed in the locomotive cab, where they are well protected from injury and are conveniently accessible for inspection, the coil itself, which is the only part of the apparatus which is carried near the rails and is exposed to the weather, having no moving parts and, consequently, requiring no inspection, may be placed in a well sealed casing.

My invention will best be understood by

reference to the accompanying drawings in which—

Figure 1 shows diagrammatically a locomotive carrying a coil arranged in accordance with my invention, the coil casing being omitted; Fig. 2 is a diagram of circuit connections, and Fig. 3 is a somewhat diagrammatic view, partly in cross section, of suitable apparatus for moving the magnetic bar.

In the drawings, A represents the track rail in which is inserted a short length of rail B of non-magnetic material, such as manganese steel. Adjacent to this rail length B is placed a magnetic bar C (shown in outlines in Fig. 2) which acts as a magnetic bridge or shunt for the rail length B and is movable into a position close to the head of the rail length B, as shown in Fig. 3, or away from the rail head against the stop e. For moving the magnetic bar C I have indicated a small electric motor D connected to the bar through speed reducing gearing. The bar C may be held in the position shown in Fig. 3 by a retaining magnet E and returned to its other position by gravity. The bar may be partly counterweighted, as indicated in dotted lines in Fig. 3. The motor D and retaining magnet E may be controlled by a contact f on a signal F adjacent to the rail length B. When the signal F is cleared, the circuit is closed as indicated in Fig. 2 and the motor D drives the car to the position shown in Fig. 3, in which position it is held by the magnet E. When the signal F goes to stop position, the circuit of magnet E is opened and bar C falls away from rail B by gravity.

G represents a laminated core of the horse-shoe type which is carried on the locomotive with its poles as close to the rails as mechanical conditions will permit. H represents a winding on this core which is supplied with alternating current from a small alternating current generator I on the locomotive. This generator may be driven in any suitable manner as, for instance, from a small direct current motor J supplied from a small storage battery K on the locomotive.

L represents an impedance in series with the magnet winding H.

As long as the core G is passing over the magnetic rail A, the air gap in the magnetic circuit is comparatively small, so that the

reactance of winding H is high. When the core passes over the non-magnetic rail length B, if the signal F is clear and the magnetic bar C is close to the head of rail 5 B, the reluctance of the magnetic circuit of coil H will not be greatly changed, but if bar C is in its other position the air gap in the magnetic circuit of winding H will be very greatly increased, so that its reactance 10 will be greatly diminished. A greater current would then tend to flow, but the impedance L is made high enough so that the current is not greatly increased. The net result is to decrease the terminal voltage of 15 winding H and the flux in core G. If a magnet M is connected in shunt to winding H the voltage on the terminals of this magnet will be very greatly reduced, if the locomotive passes over the rail length B with 20 signal F at stop. Under these conditions magnet M will release its armature m, which in turn releases a valve N which is then moved by a spring so as to open the train pipe O to atmosphere and apply the 25 brake. A resetting handle n may be provided on the valve.

With the arrangement above described, a quick and positive application of the brakes will be obtained whenever an attempt is 30 made to pass a signal in stop position. The coil H and its core may be incased so as to be well protected from the weather, since no inspection of this coil is required. This casing is not shown in the drawings. If the 35 coil should become in any manner short-circuited, notice will at once be given by the magnet m which will release its armature and apply the brake. Furthermore, if the voltage of the terminal I should fail, for 40 any cause, or the circuit of the generator should be opened, the magnet M will also give an indication. The bar C and its actuating mechanism may also be well 45 enclosed from the weather. The casing both for this bar and for the magnet H should be of non-magnetic material such, for instance, as manganese sheet steel.

I do not desire to limit myself to the particular construction and arrangement of 50 parts shown and described, but aim in the appended claims to cover all modifications which are within the spirit and scope of my invention.

What I claim as new and desire to secure 55 by Letters Patent of the United States, is:—

1. In combination with the track rails of a railway, non-magnetic spaces in said rails, means for magnetically bridging the non-

magnetic spaces, a magnetic core having an open magnetic circuit carried on a vehicle 60 with its poles adjacent to the track rail, a coil on said core, means for supplying alternating current to said coil, and a device on said vehicle responsive to a decrease in the reactance of said coil. 65

2. In combination with the track rails of a railway, non-magnetic spaces in said rails, means for magnetically bridging the non-magnetic spaces, a magnetic core having an open magnetic circuit carried on a vehicle 70 with its poles adjacent to the track rail, a coil on said core, means for supplying alternating current to said coil, and a device on said vehicle responsive to a drop in the terminal voltage of said coil. 75

3. In combination with the track rails of a railway, non-magnetic spaces in said rails, means for magnetically bridging the non-magnetic spaces, a magnetic core having an open magnetic circuit carried on a vehicle 80 with its poles adjacent to the track rail, a coil on said core, means for supplying alternating current to said coil, a device on said vehicle responsive to a decrease in the reactance of said coil, and speed-controlling means on said vehicle controlled by said device. 85

4. In combination with the track rails of a railway, non-magnetic spaces in said rails, means for magnetically bridging the non-magnetic spaces, a magnetic core having an open magnetic circuit carried on a vehicle 90 with its poles adjacent to the track rail, a coil on said core, a source of alternating current on said vehicle connected to said coil, an impedance device in series with said coil, and a magnet winding in shunt to said coil. 95

5. In combination with the track rails of a railway, non-magnetic spaces in said rails, 1 means for magnetically bridging the non-magnetic spaces, a magnetic core having an open magnetic circuit carried on a vehicle with its poles adjacent to the track rail, a 1 coil on said core, a source of alternating current on said vehicle connected to said coil, an impedance device in series with said coil, a magnet winding, and connections for impressing on said magnet winding a voltage varying directly as the flux in said core. 1

In witness whereof, I have hereunto set my hand this 25th day of July, 1910.

LAURENCE A. HAWKINS.
